UNITED STATES PATENT OFFICE.

WILLIAM H. ROONEY, OF NEW YORK, N. Y.

APPARATUS FOR KEEPING POLICE-OFFICERS' RECORDS.

Application filed October 11, 1918. Serial No. 257,749.

To all whom it may concern:

Be it known that I, WILLIAM H. ROONEY, a citizen of the United States, residing in the borough and county of the Bronx, in the city and State of New York, have invented certain new and useful Improvements in Apparatus for Keeping Police-Officers' Records; and I do hereby declare the following to be a full, clear, and exact description of the invention, such as will enable others skilled in the art to which it appertains to make and use the same.

My present invention relates to improvements in apparatus for keeping police officers' records and it is intended to secure the faithful performance of their duties by patrolmen and roundsmen or other officers obliged to patrol given posts and to "turn in" at the precinct headquarters or central station at predetermined times from police boxes located at successive points along the tour of duty. The present application forms a continuation of my co-pending application Ser. No. 847,401, filed June 26, 1914, for recording devices as to so much of the subject matter as is common to both applications.

In accordance with the invention each officer is issued by the proper authority at the central station prior to departure on his tour of duty a record receiver, such as a card, having appropriate spaces on which to contain data being the record of the officer while patrolling his post. Such data is acquired at the several police boxes from recorders contained therein. The recorders are required to be operated at stated intervals by the officers and are in operative connection with a central recorder that also makes at, the precinct headquarters a record duplicate of that transferred to the officer's card. After completing their tour of duty on their return to headquarters the officers are required to surrender the record receivers or cards. A comparison may then be made between the cards and the central record and a permanent final record may be compiled therefrom.

The invention moreover aims to provide certain novel constructions, combinations and arrangements of parts for carrying out the herein-described purposes.

In the drawings, wherein like symbols, refer to like or corresponding parts throughout the several views,

Fig. 1 is a diagrammatic view of an ap-

paratus constructed in accordance with my present invention.

Fig. 2 is a fragmentary sectional view of a detail of one of the police boxes.

Fig. 3 is a horizontal sectional view taken on the line 3—3 in Fig. 2.

Fig. 4 is a fragmentary sectional view on an enlarged scale of one of the post recorders.

Fig. 5 is a sectional view taken on the line 5—5 in Fig. 4.

Fig. 6 is a view taken from the left side of Fig. 4, with parts shown broken away.

Fig. 7 is a reduced fragmentary view showing a slight modification.

Fig. 8 shows a portion of the central recorder.

Fig. 9 is a fragmentary view of Fig. 8 taken from the opposite side.

Fig. 10 is an elevational view with parts in section of one side of the central recorder.

Fig. 11 is a similar view from the opposite side.

Fig. 12 is an enlarged fragmentary view of the platen and circuit control.

Fig. 13 is a horizontal section on the line 13—13 in Fig. 12.

Fig. 14 is an enlarged view of the platen and operating mechanism.

Fig. 15 is a top plan view thereof, and

Figs. 16 to 21 inclusive show obverse and reverse faces and edge views of two forms of cards or officers' record receivers employed.

Referring to Fig. 1, A and B are two police boxes secured, for instance to lamp posts or telegraph poles on the street along which it is the duty of officers to patrol; and C represents a recorder at precinct headquarters or the central station. The two boxes are for purposes of illustration only, it being understood that one or more boxes might be included in the apparatus. The boxes are similar and a description of one will suffice for both.

The boxes are shown as having hinged thereto doors 1, provided with locks 2 by which they are secured closed. Each officer carries a key by which all of the box doors on his post may be unlocked.

I have shown a telephone apparatus 3 in a compartment in the upper part of the box, but as this telephone apparatus forms no part of my present invention I omit specific description of its construction and method of operation.

4 designates a casing shown as having a plunger 5, projecting therefrom. The casing 4 with its plunger 5, is shown as so arranged that the closing of the door 1 will 5 push the plunger 5 backward. A spring 6, or other suitable means, causes the plunger 5 to advance outwardly as the door 1 is opened. Within the casing 4 are contact points 7 and 8 which may be so disposed to- 10 wards each other that the spring which actuates the plunger 5 will cause one of these contact points to advance towards the other as the plunger 5 moves outwardly, and re-cede therefrom as the plunger is moved 15 backward.

A piece 9 is shown as fulcrumed at 10. This piece 9 is shown as provided with a hooked portion 11, and the piece 9 is shown as so fulcrumed at 10 that the portion 12 is 20 of a greater weight than the hooked portion 11. The piece 9 is so arranged that the hooked portion 11 thereof may be engaged with the eye or staple 13 on the door 1.

14 designates a magnet so arranged that 25 the portion 12 of the piece 9 may be attracted thereby. The magnets 14 and contact points 7 and 8 of all the boxes are in a circuit as shown in Fig. 1 in which there is a source of electromotive force 15.

30 Plates, as 16, 17, are shown as attached to the interior of the box or casing A by screws, as 18, 19. Between the plates 16, 17 a shaft as 20 is shown as supported. This shaft 20 may be provided with milled heads, 35 as 21.

22 designates an index or pointer shown as provided with a handle, as 23. The index or pointer 22 may have a projection 24 on the underside thereof adapted to fit into re- 40 cesses 25 in the plate 16. (Compare Figs. 4 and 6.) The index or pointer 22 may be made integral with or suitably secured to a sleeve, as 26, and a wheel, band or segment, as 27, may be made integral with, or suit- 45 ably secured to, said sleeve 26. The sleeve 26 is shown in Fig. 4 as fitting loosely on the shaft 20. The wheel, band or segment 27 may be provided with suitable characters, as, for instance, letters of the alphabet, 50 as 28.

29, 20, 31, 32 and 33 designate wheels or bands shown as mounted on the shaft 20. These wheels or bands may be normally op- 55 erated by time clock mechanism, but as the method by which such wheels or bands are operated by time clock mechanism is well known, such method need not be here par- ticularly described. One of the wheels or bands, as 29, may be provided with char- 60 acters to indicate the months of the year; another of said wheels or bands, as 30, may be provided with characters to indicate the days of the month; another of said wheels or bands, as 31 may be provided with char- 65 acters to indicate the hours of the day; an-

other of the wheels or bands, as 32, may be provided with characters to indicate the minutes of the hour; and another of the wheels or bands, as 33, may be provided with characters to indicate forenoon or afternoon. 34 70 35 designates the face or dial of the time clock mechanism which operates said wheels or bands.

A sleeve, as 35, is shown as loosely mounted on the shaft 20. A wheel or band, as 75 36 may be made integral with or suitably secured to this sleeve 35. A set screw, as 37, may be used to hold the sleeve 35 in any desired position. To adjust the sleeve 35 and the wheel or band 36 it is only necessary 80 to loosen the set screw 37, turn the sleeve 35 and with it the wheel or band 36, to any desired position, and then fasten the sleeve 35 and wheel or band 36 in such position by fastening the set screw 37. The wheel or 85 band 36 may be provided with characters to indicate the number of the box.

38, 39, designate shafts or reels to which an inked ribbon, as 40, is shown as attached. These shafts or reels may be supported 90 in any desired manner, as, for instance, be- 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 670, 671, 672, 673, 674, 675, 676, 677, 678, 679, 680, 681, 682, 683, 684, 685, 686, 687, 688, 689, 690, 691, 692, 693, 694, 695, 696, 697, 698, 699, 700, 701, 702, 703, 704, 705, 706, 707, 708, 709, 710, 711, 712, 713, 714, 715, 716, 717, 718, 719, 720, 721, 722, 723, 724, 725, 726, 727, 728, 729, 730, 731, 732, 733, 734, 735, 736, 737, 738, 739, 740, 741, 742, 743, 744, 745, 746, 747, 748, 749, 750, 751, 752, 753, 754, 755, 756, 757, 758, 759, 7510, 7511, 7512, 7513, 7514, 7515, 7516, 7517, 7518, 7519, 7520, 7521, 7522, 7523, 7524, 7525, 7526, 7527, 7528, 7529, 7530, 7531, 7532, 7533, 7534, 7535, 7536, 7537, 7538, 7539, 75310, 75311, 75312, 75313, 75314, 75315, 75316, 75317, 75318, 75319, 75320, 75321, 75322, 75323, 75324, 75325, 75326, 75327, 75328, 75329, 75330, 75331, 75332, 75333, 75334, 75335, 75336, 75337, 75338, 75339, 75340, 75341, 75342, 75343, 75344, 75345, 75346, 75347, 75348, 75349, 75350, 75351, 75352, 75353, 75354, 75355, 75356, 75357, 75358, 75359, 75360, 75361, 75362, 75363, 75364, 75365, 75366, 75367, 75368, 75369, 753610, 753611, 753612, 753613, 753614, 753615, 753616, 753617, 753618, 753619, 753620, 753621, 753622, 753623, 753624, 753625, 753626, 753627, 753628, 753629, 753630, 753631, 753632, 753633, 753634, 753635, 753636, 753637, 753638, 753639, 753640, 753641, 753642, 753643, 753644, 753645, 753646, 753647, 753648, 753649, 753650, 753651, 753652, 753653, 753654, 753655, 753656, 753657, 753658, 753659, 753660, 753661, 753662, 753663, 753664, 753665, 753666, 753667, 753668, 753669, 753670, 753671, 753672, 753673, 753674, 753675, 753676, 753677, 753678, 753679, 753680, 753681, 753682, 753683, 753684, 753685, 753686, 753687, 753688, 753689, 753690, 753691, 753692, 753693, 753694, 753695, 753696, 753697, 753698, 753699, 7536100, 7536101, 7536102, 7536103, 7536104, 7536105, 7536106, 7536107, 7536108, 7536109, 7536110, 7536111, 7536112, 7536113, 7536114, 7536115, 7536116, 7536117, 7536118, 7536119, 75361100, 75361101, 75361102, 75361103, 75361104, 75361105, 75361106, 75361107, 75361108, 75361109, 753611010, 753611011, 753611012, 753611013, 753611014, 753611015, 753611016, 753611017, 753611018, 753611019, 7536110110, 7536110111, 7536110112, 7536110113, 7536110114, 7536110115, 7536110116, 7536110117, 7536110118, 7536110119, 75361101110, 75361101111, 75361101112, 75361101113, 75361101114, 75361101115, 75361101116, 75361101117, 75361101118, 75361101119, 753611011110, 753611011111, 753611011112, 753611011113, 753611011114, 753611011115, 753611011116, 753611011117, 753611011118, 753611011119, 7536110111110, 7536110111111, 7536110111112, 7536110111113, 7536110111114, 7536110111115, 7536110111116, 7536110111117, 7536110111118, 7536110111119, 75361101111110, 75361101111111, 75361101111112, 75361101111113, 75361101111114, 75361101111115, 75361101111116, 75361101111117, 75361101111118, 75361101111119, 753611011111110, 753611011111111, 753611011111112, 753611011111113, 753611011111114, 753611011111115, 753611011111116, 753611011111117, 753611011111118, 753611011111119, 7536110111111110, 7536110111111111, 7536110111111112, 7536110111111113, 7536110111111114, 7536110111111115, 7536110111111116, 7536110111111117, 7536110111111118, 7536110111111119, 75361101111111110, 75361101111111111, 75361101111111112, 75361101111111113, 75361101111111114, 75361101111111115, 75361101111111116, 75361101111111117, 75361101111111118, 75361101111111119, 753611011111111110, 753611011111111111, 753611011111111112, 753611011111111113, 753611011111111114, 753611011111111115, 753611011111111116, 753611011111111117, 753611011111111118, 753611011111111119, 7536110111111111110, 7536110111111111111, 7536110111111111112, 7536110111111111113, 7536110111111111114, 7536110111111111115, 7536110111111111116, 7536110111111111117, 7536110111111111118, 7536110111111111119, 75361101111111111110, 75361101111111111111, 75361101111111111112, 75361101111111111113, 75361101111111111114, 75361101111111111115, 75361101111111111116, 75361101111111111117, 75361101111111111118, 75361101111111111119, 753611011111111111110, 753611011111111111111, 753611011111111111112, 753611011111111111113, 753611011111111111114, 753611011111111111115, 753611011111111111116, 753611011111111111117, 753611011111111111118, 753611011111111111119, 7536110111111111111110, 7536110111111111111111, 7536110111111111111112, 7536110111111111111113, 7536110111111111111114, 7536110111111111111115, 7536110111111111111116, 7536110111111111111117, 7536110111111111111118, 7536110111111111111119, 75361101111111111111110, 75361101111111111111111, 75361101111111111111112, 75361101111111111111113, 75361101111111111111114, 75361101111111111111115, 75361101111111111111116, 75361101111111111111117, 75361101111111111111118, 75361101111111111111119, 753611011111111111111110, 753611011111111111111111, 753611011111111111111112, 753611011111111111111113, 753611011111111111111114, 753611011111111111111115, 753611011111111111111116, 753611011111111111111117, 753611011111111111111118, 753611011111111111111119, 7536110111111111111111110, 7536110111111111111111111, 7536110111111111111111112, 7536110111111111111111113, 7536110111111111111111114, 7536110111111111111111115, 7536110111111111111111116, 7536110111111111111111117, 7536110111111111111111118, 7536110111111111111111119, 75361101111111111111111110, 75361101111111111111111111, 75361101111111111111111112, 75361101111111111111111113, 75361101111111111111111114, 75361101111111111111111115, 75361101111111111111111116, 75361101111111111111111117, 75361101111111111111111118, 75361101111111111111111119, 753611011111111111111111110, 753611011111111111111111111, 753611011111111111111111112, 753611011111111111111111113, 753611011111111111111111114, 753611011111111111111111115, 753611011111111111111111116, 753611011111111111111111117, 753611011111111111111111118, 753611011111111111111111119, 7536110111111111111111111110, 7536110111111111111111111111, 7536110111111111111111111112, 7536110111111111111111111113, 7536110111111111111111111114, 7536110111111111111111111115, 7536110111111111111111111116, 7536110111111111111111111117, 7536110111111111111111111118, 7536110111111111111111111119, 75361101111111111111111111110, 75361101111111111111111111111, 75361101111111111111111111112, 75361101111111111111111111113, 75361101111111111111111111114, 75361101111111111111111111115, 75361101111111111111111111116, 75361101111111111111111111117, 75361101111111111111111111118, 75361101111111111111111111119, 753611011111111111111111111110, 753611011111111111111111111111, 753611011111111111111111111112, 753611011111111111111111111113, 753611011111111111111111111114, 753611011111111111111111111115, 753611011111111111111111111116, 753611011111111111111111111117, 753611011111111111111111111118, 753611011111111111111111111119, 7536110111111111111111111111110, 7536110111111111111111111111111, 75361101111111111111

55 and 56 into a series of segmental spaces. The spaces are numbered 2, 4, 6, etc., on the obverse side of the card shown in Fig. 16; and 1, 3, 5, etc., on the reverse side of the card shown in Fig. 17. The numbers may indicate the order in which the spaces are to be used. The spaces on the obverse side of the card are arranged about a central space 57 for containing data identifying the 10 officer entrusted with same, for instance with the patrolman's shield number. There is a similar central space 58 on the reverse side of the card for receiving other data. In Fig. 16 the space between the lines 55 and 15 56 bears an impression received at one of the boxes. This impression indicates that the card was stamped at box 17, which is designated as box A on the post of Patrolman No. 4953; and that the impression was 20 made on March 2nd at 8:21 P. M. If the officers are required to "turn in" every half hour the octagonal card provides for receiving an officer's record on an eight hour tour of duty. The hexagonal card shown in 25 Figs. 19 to 21 is similar in all substantial respects to the octagonal card, with the exception of the shape and it provides for containing a six hour record.

30 A platen 59 is arranged to move up beneath the card after same has been inserted through the slit 46 in the casing and to bring this card and the inked ribbon 40 against the characters on the various type wheels or bands. The platen 59 is operated by means 35 of a handle 60, located so as to be accessible to the officer. Reference is to be had more particularly to Figs. 14 and 15 for understanding the construction of the platen operating mechanism.

40 Within the outer box or casing A are brackets 61, and mounted between these brackets is a shaft 62. A hub 63 is loosely mounted on the shaft 62. Extending from the hub 63 is a rod 64 provided with the 45 handle 60.

65 designates a sector shown as made integral with the hub 63. The outer edge of this sector 65 is shown as provided with notches 66 and 67 and between these notches 66 and 50 67 are teeth 68.

69 designates a tension spring shown as attached to the sector and to the box.

70 designates a spring, one end of which is shown as secured to a pin 71. The other 55 end of this spring is shown as secured to a pin 72 on the arm 73. Shown as also pivoted on the pin 72 is a bar 74 having a forked or slotted end adapted to straddle the pin 71.

75 designates a hub shown as pivoted on 60 the shaft 62. 73 designates an arm shown as provided with the platen 59. 76 designates contact pieces of conducting material in electrical communication with each other. Said pieces 76 are movable with said 65 plate 59.

The arm 73 is shown as provided with a pin 77, to which pin 77 there is shown as pivoted the upper end of a piston rod 78. Said piston rod 78 has a piston working in a dash pot or cylinder 79. Said dash 70 pot or cylinder 79 may be pivotally mounted on a pin 80 secured to the box or casing.

81 designates a toggle lever shown as pivoted to a pin 82 on the sector 65 and to a pin 83 on a bracket 84, secured to the outer 75 box or casing.

85 designates a spring, one end of which is shown as attached to said bracket 84. The other end of said spring 85 is shown as attached to the toggle lever 81.

80 The arm 73 is shown as provided with a pin 86. 87 designates a pawl shown as hinged on a pin 88. One end of said pawl 87 is shown as arranged within reach of the outer edge of the sector 65. The other end 85 of this pawl 87 is shown as attached to one end of a spring 89. The other end of said spring 89 is shown as fastened to a pin 90. 91 is a stop.

In Figs. 8, 9, 10 and 11:—

90 Interior contact points as 92, 93, 94, 95, etc. (Fig. 11) are shown as arranged within reach of the contact pieces 76 on the platen 59. Said contact points may be suitably arranged on plates or pieces 96 and 97 of 95 conducting material.

98 designates a contact point also arranged within reach of the contact pieces 76 on the platen 59.

99, 100, 101, 102 etc. designate exterior 100 contact points also shown as arranged within reach of the contact pieces 76. These contact points are shown as arranged on said plates 96 and 97. The plates 96 and 97 are shown as faced with non-conducting material. Suitable openings will, of course, be provided for the contact points arranged on the plates or pieces 96 and 97.

103 and 104 designate openings below the 110 plates 96 and 97.

105 designates an escapement intended to control the movement of a wheel 106, affixed to a shaft 107. To this shaft 107 there is also affixed the wheel 108 provided with characters to indicate box numbers.

115 109 designates a worm arranged on the shaft 107, and 110 designates a pin extending from the shaft 107. This pin 110 may be an extension of the coil of the wire of which the worm 109 is formed.

111 designates a spring, one end of which is shown as fastened to the shaft 107. The other end of this spring 111 is shown as impinging against the face of the pinion 112, which pinion 112 is shown as mounted on 125 said shaft 107.

120 113 designates a toothed wheel shown as meshing with the pinion 112, and 114 designates a coiled spring intended to drive the wheel 113. The wheel 113 is shown as 130

mounted on a shaft 115. 116 is a balance wheel shown as affixed to said shaft 115.

117 designates a spring, one end of which is shown as fastened to a collar 118, secured 5 to the shaft 115. The other end of this spring 117 is shown as attached to the hub 119 of the balance wheel 116.

120 designates a toothed wheel securely mounted on the shaft 115. Shown in contact with the toothed wheel 120 is a pawl 121 (Fig. 10), which pawl 121 is shown as arranged on an arm 122, fastened to a shaft 123. 124 designates a spring, one end of which is shown as fastened to the arm 122, 15 and the other end of which is shown as impinging against the pawl 121 and thereby holding the pawl 121 in engagement with the toothed wheel 120.

Attached to the shaft 123 is an arm which 20 carries an armature 125. Shown as affixed to the arm which carries the armature 125 is an arm 126. This arm 126 is so arranged as to be within reach of an arm 127.

In Fig. 11:—

25 131 designates an arm affixed to the shaft 123, and 132 designates a spring, one end of which is shown as attached to said arm 131.

A hammer 133 is shown as carried by the arm 131.

30 134 designates a spring shown as arranged on the arm 131. This spring 134 is shown as fastened at 135 to a pawl 136. Said spring 134 holds the pawl 136 in contact with a ratchet wheel 137 mounted on a shaft 138.

35 A toothed wheel 139 is shown as also loosely mounted on said shaft 138.

140 designates a wheel preferably faced with india rubber or resilient material. Said wheel 140 is shown as mounted at 141 40 on an arm 142, and said arm 142 is shown as hinged at 143. 144 designates a spring, one end of which is shown as fastened to the arm 142.

145 designates a guard intended to hold 45 the central record receiver or tape 146 out of engagement with the wheel or band 108 until the hammer 133 strikes the tape 146 against said wheel or band 108. The tape 146 is shown as fed from a reel 147 and as 50 passing under the guard 145 and another guard 148 on its way between the wheels 139 and 140.

The contact point 98 is in electrical communication with the magnets 149 through 55 the connections 150 and 151. A magnet 154 is in a circuit 152 and 153. A source of current 155 serves both the circuits 150, 151 and 152, 153. The magnet 154 controls the release of the escapement 105.

60 Assuming the box to be presently operated by Patrolman Doe to be one of a series of patrolmen's boxes in electrical communication with a central station apparatus, the wheel or band 108 of the central station 65 apparatus may be provided with characters

intended to designate seven boxes. Also assume that the box which Patrolman Doe is required to presently operate be box three of such series. This box may be provided with three interior points 92, 94 etc. on the 70 plate 96, and three interior contact points 93, 95 etc. on the plate 97.

To operate the platen 59 whereby his card may be stamped Patrolman Doe pulls down the handle 60. This action causes the contact pieces 76 on the platen to first come in contact with the lowermost contact points on the plates 96 and 97. Thereby an electric circuit is completed through the plates 96 and 97, the conductors 152 and 153, and the 80 magnet 154.

As a result:—

1. The magnet 154 will shift the escapement 105 and the escapement wheel 106 will thereby become free to advance the distance 85 of one tooth;

2. When the wheel 106 is freed to move one tooth the spring 114 impels the wheel 113 and the wheel 113 is thereby caused to move the pinion 112. In its movement, the 90 pinion 112, which is affixed to the shaft 107, turns the wheel 108 one step.

3. When the contact pieces 76 on the platen 59 cease engagement with the lowermost contact points on the plates 96 and 97 95 the electric circuit is broken and remains broken until the contact pieces 76 come into engagement with the next contact points 94 and 95.

4. When the contact pieces 76 come into 100 engagement with the contact points 92 and 93 the electric current will have been again reversed and when the electric circuit is completed the escapement 105 will be drawn again in the first direction as mentioned in 105 operation 1, and the wheel 106 will thereby become free to advance the distance of one tooth and the wheel 108 will turned a third step.

After passing the contact points 92 and 110 93 the contact pieces 76 in their upward movement will come into contact with point 98. Thereby the magnets 149 will become energized through the circuit formed by the conductors 150 and 151. The energization 115 of these magnets will cause the following results:—

(a). Said magnets will attract the armature 125. This will cause the shaft 123 to turn; 120

(b). This movement of the shaft 123 will cause the arm 131 to ascend and thereby the hammer 133 will be caused to strike the tape 146 against the character presented to said tape by the wheel or band 108;

(c). The same movement of the shaft 123 which causes the arm 131 to ascend raises the arm 122 and with it the pawl 121 and this movement of the pawl 121 turns the toothed wheel 120. Thereby the shaft 115 130

is turned and the spring 117 may be maintained at a desired tension.

When the magnets which have attracted the armature 125 are de-energized by the 5 contact pieces 76 ceasing to engage the contact point 98 the armature 125 will be released from the attraction of its magnets and drop down. This movement of the armature 125 will cause the shaft 123 to 10 move backward. As the shaft 123 moves backward the arm 131 will descend and the hammer 133 will cease to press the tape 146 against the wheel or band 108. The spring 132 will aid in pulling down the arm 131. 15 As the arm 131 moves downward the pawl 136 will turn the ratchet wheel 137 and thereby the shaft 138. This movement of the shaft 138 will turn the toothed wheel 139 between which and the wheel 140 the tape 20 146 is arranged. In turning the toothed wheel 139 will, of course, carry the tape 146 forward and thereby the tape will be in readiness to receive another imprint from the wheel or band 108.

25 156 designates a pawl shown as held in engagement with the ratchet wheel 137 by a spring 157.

The contact pieces 76 are resilient and so disposed towards each other that when pressed 30 sure on the handle is released and the contact pieces descend after engagement with the contact point 98 they will be spread apart by the guides 158 and 159 and guided on the outside of the plates 96 and 97.

35 When the contact pieces 76 come into contact with the contact pins 99 and 100 the escapement 105 will be again oscillated and the wheel 106 will thereby become free to advance the distance of one tooth and the 40 wheel 108 will be turned a fourth step.

When the contact pieces 76 come into contact with the contact pins 101 and 102 the wheel 108 will be turned a fifth step; when the contact pieces 76 come into contact with 45 the next pair of outside pins the wheel 108 will be turned a sixth step; and when the contact pieces 76 come into contact with the following pair of contact pins the wheel 108 will be turned a seventh step.

50 After leaving the last pair of contact points the contact pieces 76 will be allowed by the guides 160 and 161 to approach each other and after passing from reach of the guides 160 and 161 they will enter the open 55 spaces 103 and 104. In this position they will be out of electrical contact.

The guides 158, 159, 160, 161 will of course be of non-conducting material or faced with non-conducting material.

60 The contact pieces 76 will be so disposed towards each other that when they are moved upward the inner ends of the guides 160 and 161 will cause said contact pieces 76 to move towards each other and enter the 65 space between the plates 96 and 97.

If it be desired to use the box illustrated in Fig. 11 for box 4 all that will be necessary will be to withdraw two pins from position on the outside of the plates 96 and 97 and insert said pins opposite to each other 70 on the inside of said plates 96 and 97.

I will now describe the method of operation of the apparatus illustrated in Fig. 14 and 15.

When the handle 60 is pulled down, the 75 sector 65 will rock on the shaft 62 and move to a position indicated by broken lines in Fig. 14. The pawl 87 will tick over the notches 68. These notches 68 will be so shaped that, until the notch 66 is reached, 80 the pawl 87 will prevent the sector 65 from being turned backward. These notches 68 will be so spaced with reference to the contact points 92, 93, 94 etc. that the pawl 87 will lock in a notch each time the contact pieces 76 are out of contact with the contact points 92, 93, 94 etc.

As the handle 60 is being pushed down and the sector 65 rocks forward, the stretch of the springs 69 and 70 will cause the arm 90 73 to rock upwardly on its pivot 62 at a speed relatively slower than that of the sector, and which may be regulated by the dash pot 79 to which the arm 73 is connected. In this way, no matter how quickly the handle 60 is pushed down, the arm 73 will follow up the sector at a predetermined speed, thus insuring sufficient time for the contact pieces 76 to make proper contact with the contact 95 points 92, 93 etc.

When the sector 65 has reached the position shown in broken lines in Fig. 14 the toggle lever 81 will have been straightened out as shown in broken lines. Further movement is prevented by the lug 91 on the 100 bracket 84, lying in the path of the lower member of said toggle lever 81.

The sector 65 having been moved its full stroke forward, the springs 69 and 70 stretched and this position maintained by 110 the straightened toggle lever 81, the arm 73 moves up slowly under the influence of the spring 70 and retarded by the dash pot 79, until it has completed its forward stroke. The pin 86, secured in the arm 73 engages 115 the lower member of the toggle lever 81 and pushes it out of straight line thus breaking the toggle joint as shown in dotted lines in Fig. 14 and allowing the sector to return to its normal position by means of the spring 120 69. When the sector has reached its forward position the deep notch 67 will have presented itself to the pawl 87 and said pawl will then straighten and take a position which will allow the sector to return to 125 normal position.

As the sector rocks backward, the tension of the spring 70 relaxes.

Should the patrolman fail to pull the handle all the way down and not complete the 130

full forward movement of the sector 65, the pawl 87 would lock the sector in one of the notches 68. The arm 73 would immediately follow up until the end of the slot in the 5 bar 74 butted against the pin 71, where it would come to rest.

When the sector has reached its backward position, the deep notch 66 will have presented itself to the pawl 87 and said pawl 10 can then straighten itself out and the sector is then free to be again moved forward.

162 designates a face or dial of a time clock mechanism located at a central station or office. This time clock mechanism may 15 operate a series of bands or wheels, as 163, 164, 165, 166 and 167. The band or wheel, as 163, may be provided with characters to indicate the months of a year; the band or wheel 164 may be provided with characters 20 to indicate the days of a month; the band or wheel 165 may be provided with characters to indicate the hours of a day; the band or wheel 166 may be provided with characters to indicate the minutes of an hour; and 25 the band or wheel 167 may be provided with characters to indicate forenoon or afternoon.

The hammer 133 also brings the tape 146 against these bands or wheels 163, 164, 165, 30 166 and 167.

I will now describe my improvement as applied to a police patrol system.

As patrol boxes are ordinarily used in a police patrol system a patrolman is required 35 to signal to a central office or station from either end of his beat at certain intervals of time during his tour of duty, as, for instance, every half hour. If a tour of duty be eight hours and the patrolman be required 40 to signal a central station or office each half hour he will, if he performs his duty, have signalled the central office or station sixteen times during a tour of duty.

Supposing the tour of duty of Patrolman 45 Doe to be eight hours and that he is required to signal the central station or office each half hour during these eight hours, and further suppose that the boxes from which he is required to register be boxes 3 50 and 4 of a series of boxes connected with one apparatus at the central station or office. Also assume that box 3 is his box A and that box 4 is his box B. Patrolman Doe may be given an octagonal shaped card divided on 55 each face thereof into eight sections which may be suitably numbered as shown in Figs. 16 to 18. At eleven o'clock in the forenoon the time arrives for Patrolman Doe to signal the central station or office from box 3 which 60 is his box A. He goes to box 3 opens the door thereof, and turns the index or pointer 22 to A. Thereby the sleeve 26 and the wheel, band or segment 27 will be so adjusted that a character, as A on the wheel, band or segment 27, will be placed in

proper position to enable such character, as A, on the wheel, band or segment 27, to be registered on a paper or card inserted in the slit or opening 46. The time clock mechanism will have brought the wheels or bands, as 29, 30, 31, 32, 33, into such position as to enable characters on said wheels or bands, to be registered on the paper or card inserted in the slit or opening 46. 3 being the number of the box which is being operated by Patrolman Doe the wheel or band 36 will have been properly locked by the set screw 37 in such position as to enable a character as 3, on the wheel or band 36 to be registered on a paper or card inserted in the slit or opening 46. 75 80

Patrolman Doe inserts his card 47 into the slit or opening 46 of box 3 in such way as to present subdivision 1 of his card to characters on the wheel, band or segment 85 27, the wheels or bands 29, 30, 31, 32, 33, and the wheel or band 36. After properly inserting his card 47 into the slit or opening 46 of box 3 he pulls down the handle 60. This action causes the contact pieces 76 to 90 come into engagement with the contact points as heretofore described and as the contact pieces 76 come into engagement with each of these last mentioned contact points the circuit is closed thereby and the energization of the magnets 149 causes the wheel or band 108 to be so turned that after the contact pieces 76 have passed over the several contact points a character as 3, on the wheel or band 108 will have come into such 100 position that it may be registered. The time clock mechanism at the central office will, of course, have brought the wheels or bands 163, 164, 165, 166, 167, into such position as to enable characters on said last mentioned wheels or bands to be registered on the tape 146 of the central office apparatus. 95

When Patrolman Doe has pulled down the handle 60 sufficiently far, his card 47 will come into contact with characters on the 110 wheel, band or segment 27, the wheels or bands 29, 30, 31, 32, 33, and the wheel or band 36, and thereby there will be registered within subdivision 1 of his card 47, characters indicating the particular box of the two or 115 more boxes which Patrolman Doe is required to operate during his tour of duty, as for instance box A, together with the month, day of month, hour, minute, forenoon or afternoon and box number. As already explained, the impulse sent over the line when the pieces 76 come into contact with point 98 causes the magnets 154 to operate the hammer 153 and thereby the tape 146 will receive the impressions from the wheels 108 and 163, 164, 165, 166, 167, thereby registering on the tape of the apparatus at the central office or station the number of the box, 120 and the month, day of month, hour, minute and forenoon or afternoon. 125

When Patrolman Doe has so stamped his card the handle 60 and platen 59 will return to initial position and the wheel 108 of the central office or station apparatus will return to zero or blank, and the tape of the central office or station apparatus will be advanced so as to enable said tape to receive another impression.

When Patrolman Doe finishes signalling from box 3 he closes the door of that box. At half past eleven o'clock in the forenoon the time arrives for him to signal the central station or office from box 4—his box B. To signal from box 4 and register on his card from that box he will, of course, have had to travel from box 3 to box 4. When the time arrives to report from box 4 he opens the door 1 of that box and turns the index or pointer 22 therein to B. Thereby the sleeve 26 and the wheel, band or segment 27 will be so adjusted that a character, as B, on the wheel, band or segment 27 will be brought into proper position to enable such character, as B, to be registered on his card when the card is inserted in the slit or opening 46. The operation is otherwise the same as that of box A.

Should a patrolman attempt to use box 3 twice in succession the marking made on his card by the fixed wheel or band 36 will indicate that fact, and the registration at the central station or office will indicate that box 3 had been operated and that box 4 had not been operated.

In practice I prefer that a card given a patrolman when he goes on duty shall have his number placed thereon and that when the patrolman returns to the central station after his tour of duty has ended the card be surrendered. The card may be preserved as a permanent record indicating what boxes the patrolman operated during his tour of duty on a particular day and the exact time each box was operated. For convenience, if desired, cards furnished patrolmen may be suitably stamped with the date of the receipt thereof by the patrolman.

Roundsmen charged with the duty of supervising the performance of the duties of patrolmen, may also be furnished with cards like those furnished patrolmen, but to differentiate the cards of roundsmen from those of patrolmen I prefer to make the card of roundsmen and patrolmen of different colors and I prefer to so arrange matters that if patrolmen are required to register from their boxes on the hour and half hour roundsmen be required to register fifteen minutes later than the patrolmen. By this arrangement if a patrolman fails to signal the central station or office from the box from which he should have reported such failure can be reported to the roundsman when he signals the central station or office, and the roundsman then set about investi-

gating the cause of the failure of the patrolman to signal. In practice roundsmen are given charge of certain portions of a precinct and the records made by a roundsman on the card carried by him will show from 70 what boxes he reported during his tour of duty and will also show whether he has conformed to the rules prescribed for the performance of his duty, insofar as relates to the boxes from which he should register and 75 the time of registering from each box.

The object of my invention so far as it relates to a police patrol system is to compel a patrolman to patrol under danger of ready detection. By obliging patrolmen to 80 use the card which I have described, a patrolman must patrol back and forth on his post carrying his card with him and stamping it at each end of his post, and his failure to do so will not only be shown by the card 85 itself but may be immediately detected at the central station because of the failure to operate the central office or station apparatus from a particular box, and the attendant at the central station or office may cause an immediate investigation to be made of the failure to report from such box and cause assistance to be furnished the patrolman should he require it. As already indicated, roundsmen will also be obliged to patrol 90 their sections constantly in the same manner as patrolmen are required to patrol their posts.

Patrolmen and roundsmen may be required to make memoranda explaining failures to operate their patrol boxes on time and this memoranda may be collected at the end of the tours of duty and checked up with patrolmen's and roundsmen's cards and with the tape records at the central station 100 or office. My invention therefore, permits of the establishment of a patrol system where the work of the patrolling force may be effectually supervised and in which patrol duty cannot be shirked without danger 105 of easy and prompt detection.

What I claim as my invention and desire to secure by Letters Patent is:—

1. In a device of the character described, the combination of a movable platen, 115 spaced-apart contacts near said platen, a contact carried by the platen and moved thereby successively into engagement with said first mentioned contacts, means for operating said platen, speed-reducing connections between said operating means and platen for moving the contact carried by the platen slowly over said first mentioned contacts, and means for restoring the platen to initial position after each actuation. 120

2. In a device of the character described, the combination of a central station having an electrically controlled apparatus, a post, a series of spaced apart contacts located at the post and in connection with the appa- 130

- ratus at the central station, a movable means to initial position until the same have executed their full movements.
5. In combination, a movable platen, a platen and adapted to move successively into engagement with each of said spaced contacts, operating means for said platen, speed-reducing connections between said operating means and platen for causing the contact carried thereby to move slowly from one to the other of said spaced apart contacts, without regard to the quickness with which said operating means is moved, and means for restoring the platen to initial position after each actuation.
6. In combination, a movable platen, a series of contacts located close to the platen, a platen and adapted to move successively into engagement with the first mentioned contacts, operating means for causing the platen to be moved throughout a full stroke to cause the contact carried thereby to move successively into engagement with all of the first mentioned contacts, and means for restoring the platen to initial position after each actuation.
7. In combination, a movable platen, a platen and adapted to move successively into engagement with each of said spaced contacts, operating means for said platen, speed-reducing connections between said operating means and platen for causing the contact carried thereby to move slowly from one to the other of said spaced apart contacts without regard to the quickness with which said operating means is moved, and means for restoring the platen to initial position after each actuation.
8. In combination, a platen, a pivoted arm carrying said platen, a pivoted sector, a cooperating contact on the plate movable between said sector and arm, means for allowing the slow movement of the arm and platen, speed-reducing connections between said operating means and platen for causing the platen to be moved throughout a full stroke to cause the contact carried thereby to move successively into engagement with all of the first mentioned contacts, and means for restoring the platen to initial position after each actuation.
9. In combination, a platen, an arm carrying the same, a swinging sector having notches in its edge and deep recesses at the opposite ends of the notches, a pivoted pawl adapted to engage said notches and being engageable by the hand, capable of swinging freely in said recesses, for moving said platen, intermediate means disposed between said sector and arms, means for allowing only the slow movement of the latter, means for compelling said operating means to be moved throughout its full movement, and means for restoring the platen to initial position after each operation.
10. In combination, a platen, an arm carrying the platen, a swinging sector, a pin on said sector, a bar carried by said arm and having a slotted upper end engaging contact arm carried thereby, a succession of contacts disposed in position to be successively engaged by said contact arm when the platen is moved, hand engageable means for operating said plate, spring means for accomplishing the relatively slow movement of the latter, means for preventing the backward movement of the platen until the same has been moved to the end of its movement, and means for automatically restoring the platen to initial position.
11. In combination, a platen, a swinging sector, a handle for swinging said sector, spring means for holding said sector in initial position, a toggle-lever connected to said sector for holding the same at the other limit of its movement, means for yieldingly carrying the platen, a moving said arm following the movement of the sector, a dash pot connected to said arm, contacts in position to be engaged by said contact arm, operating means for the platen, and break said toggle joint when the arm carries at the limit of its movement.
12. In combination, a movable platen, spring contact arms carried thereby, insulating bars having openings, contacts for restoring the operating means to original position, and means for preventing the restoration of the platen and operating means for effecting the slow movement of said platen relatively to said operating means, means for restoring the operating means to original position, and means for preventing the restoration of the platen and operating contact arms, guides above and below said

insulating bars for guiding the spring arms successively on the insides and outsides of said bars, and separate contacts above the upper guides and means for accomplishing the slow movement of the spring arms over said contacts.

13. In an apparatus for keeping police officer's records, the combination of a normally locked police box accessible to properly constituted officers, a casing contained within said box inaccessible to said officers and having a slot therein for the insertion of a record card carried by each officer, time-stamping mechanism within said casing, an officer's box designation device also contained within said casing and bearing a variety of indicia, means for manually setting said designation device extending upon the exterior of the casing but within said box, said manual setting means having associated therewith indicating means for showing on the exterior of the casing the position of adjustment of the interior designation device, said manual setting means also having means to yieldably hold the interior designation device in set position, and a platen adapted to engage said card within the casing and to force the card against said time-stamping mechanism and said designation device, said platen having actuating means extending upon the exterior of the casing but within said box.

14. In an apparatus for keeping police officers' records, the combination of a normally-locked police box accessible to properly constituted officers, a casing within the box inaccessible to such officers and having a slot therein to receive a record card carried by each officer, time-stamping mechanism within said casing, an adjustable officer's box designation device mounted wholly within said casing and alongside said time-stamping mechanism, said designation device having a succession of indicating characters thereon corresponding to the box designations of a number of officers whose beats intersect at the box, manual setting means connected to said box designation device and extending on the exterior of the casing yet within the protection of said box, an index moving with said manual means over one side of the casing, such side of the casing having indicating characters thereon corresponding to the characters upon said interior designation device, said index and said casing also having yieldable locking means for holding the designation device in the succession of positions, a platen movably mounted within the casing for moving said card against said time-stamping mechanism and said designation device, and an actuating handle connected to the platen and extending beyond said casing.

15. In an apparatus for keeping police officers' records, the combination of a nor-

mally-locked police box accessible to officers, a casing within the box inaccessible to officers and having a slot therein to receive record cards carried by the officers, time-stamping mechanism within said casing, a fixed box numbering device in the casing alongside said time-stamping mechanism, an officer's box designation device also within the casing alongside said time-stamping mechanism and having a succession of indicating characters adapted to be brought singly into printing position, a rotatable handle connected operatively with said box designation device and extending upon the exterior of said casing for manual operation by the officers, an index movable with said rotatable handle, said casing having indicating characters spaced on said casing to which the index points, said index and casing having yieldable locking means for holding the pointer opposite any one of said indicating characters, an oscillating platen within said casing adapted to forcibly press the record card against said time-stamping mechanism, the box numbering device and the officer's designation device, and a handle for manually shifting said platen extending on the exterior of the casing.

16. In combination, a central station, time-controlled stamping mechanism at the central station, a post box, movable designating means for the post box at the central station, spaced contacts at the post box, a contact-piece movable into successive engagement with the spaced contacts, circuits including the spaced contacts, means included in said circuits to advance the designating means a predetermined degree, a further contact at the post box adapted to be engaged by said contact-piece subsequent to the engagement by the latter of the spaced contacts, means in circuit with such further contact whereby a tape at the central station may be pressed against the stamping mechanism and designating means, and means for returning the designating means to initial position after each stamping of the tape.

17. In combination, a central station, time-controlled stamping mechanism at the central station, a post box, movable designating means for the post box at the central station, spaced contacts at the post box, a contact-piece movable into successive engagement with the spaced contacts, means in circuit with said spaced contacts and contact-piece to advance the designating means a predetermined degree according to the number of spaced contacts, speed-reducing connections to regulate the speed with which the contact-piece may be moved, a further contact at the post box adapted to be engaged by said contact-piece subsequent to the engagement by the latter of the spaced contacts, means in circuit with such further contact whereby a tape at the

- central station may be pressed against the stamping mechanism and designating means, and means for returning the designating means to initial position after each stamping 5 of the tape.
18. In combination, a central station, time-controlled stamping mechanism at the central station, a post box, movable designating means for the post box at the central 10 station, spaced contacts at the post box, a contact-piece movable into successive engagement with the spaced contacts, means in circuit with said spaced contacts and contact-piece to advance the designating means a 15 predetermined degree according to the number of spaced contacts, a further contact at the post box adapted to be engaged by said contact-piece subsequent to the engagement by the latter of the spaced contacts, means 20 in circuit with such further contact whereby a tape at the central station may be pressed against the stamping mechanism and designating means, means for restoring the contact-piece to initial position, and means operated incident to the return of the contact-piece for restoring the designating means to 25 its original position.
19. In an apparatus for keeping police officers' records, a plurality of recorders 30 on the officer's post adapted to consecutively receive a single record card carried by the officer, a recorder at a central station, and connections whereby the central station recorder is actuated whenever the post recorder 35 is actuated.
20. In an apparatus for keeping police officers' records, a plurality of recorders located respectively at the various officers' 40 posts adapted to receive a record card carried by the officer and having a plurality of divided spaces thereon provided to receive different data at each consecutive recorder for forming the officer's record, a recorder at the central station, and connections whereby 45 the central station recorder is actuated whenever the post recorder is actuated.
21. In an apparatus for keeping police officers' records, a plurality of differently-marking recorders on officers' posts adapted 50 to record their respectively different markings on a single record card insertible in and removable from the recorders by an officer, and a central recorder having connection to all of the post recorders and actuated there- 55 by for showing at what post recorders officers are at any time making records on their cards.
22. In apparatus for keeping police officers' records, a central recorder, and a plurality 60 of post recorders having connection to the central recorder and adapted to receive and permit withdrawal of record cards carried in the custody of officers for receiving record data from the several post record- 65 ers, the same being the record of the officer's tour of duty, said post recorders adapted to actuate said central recorder at any time and independent of the condition of the central recorder.
23. In an apparatus for keeping police officers' records, the combination of a plurality of recorders on the officers' posts adapted to receive a record card carried by the officer, a central recorder, and means controlled by each post recorder for first putting the central recorder in condition to record the respective designation of the post recorder and secondly causing the central recorder to make a record of such designation. 70
24. A police officer's record card adapted 75 to be carried on the person of the officer and also adapted to be inserted part by part in recorders on the officer's post, said card having laid off thereon segmental spaces defining such parts adapted to consecutively receive data at the several recorders for forming a complete record of the officer's tour of duty. 80
25. A police officer's record card formed 85 with straight edges, segmental spaces laid off on both sides of said card, such spaces adapted to receive data on the tour of duty which forms the officer's record, means to designate the order in which the spaces are to be used to receive such data, and a space 90 on the card to receive data identifying the officer carrying same. 95
26. In a device of the class described, a series of time controlled type wheels, a manually controlled type member associated therewith, a normally stationary type wheel for printing a box number, a series of electric contacts adapted to be connected with a recording device, comprising a lever for bringing a card into engagement with the type wheels, the end of the lever when operated completing a circuit through certain contacts corresponding in number with the number of the box. 100
27. In a device of the class described, a shaft, a series of time controlled type wheels carried thereby, a manually controlled type member on said shaft, a type member arranged to indicate the number of a box in a series of boxes, means for adjusting said member on the shaft and for retaining it when adjusted, and means for printing from said type wheels and member simultaneously and causing a plurality of electrical impulses to be transmitted, said means last mentioned including a series of contacts and a platen and lever, the latter engaging electrical contacts corresponding in number with the number of the box. 110
